JESSE C. OWENS, OF LOS ANGELES, CALIFORNIA

TOILET-TANK FLUSH VALVE

Application filed April 26, 1928. Serial No. 273,120.

My invention relates to a flushing valve that is especially designed for use in connection with closet bowls and the like, and the principal objects of my invention are, to 5 generally improve upon and simplify the construction of the existing forms of flushing valves; to provide a valve of the character referred to that may be easily and inexpensively manufactured and installed; to 10 provide a construction wherein the pressure of the water from the source of supply, for instance the city water mains, is utilized for compressing air that is effective, when the valve is manually opened, in adding force to 15 the flushing water that discharges through the valve; further, to provide in a flush valve, a float that is utilized for normally closing the outlet from the valve; and further, to provide a flush valve that is strong 20 and substantial in construction and having comparatively few operating parts, thereby minimizing the liability of the valve becoming inoperative and ineffective due to disarrangement of the parts.

25 Further objects of my invention are, to provide a toilet tank flush valve that is practically silent in operation during the flushing action and during the refilling of the tank, further, to provide a device of the character referred to that is economic in the use of 30 water and which is non-leaking when properly installed, and further, to provide a simple and efficient means including ducts and check valves for permitting air to enter 35 the tank and valve to permit the water under pressure to readily discharge from the tank and pass thru the valve to effect the flushing action.

40 My present invention is an improvement on the pressure flushing device disclosed in U. S. Letters Patent No. 1,566,769, issued to me December 22, 1925, and also my co-pending application for U. S. Letters Patent, filed July 16, 1926, Serial No. 122,815.

45 With the foregoing and other objects in

view, my invention consists in certain novel features of construction and arrangement of parts that will hereinafter be more fully described and claimed and illustrated in the accompanying drawings, in which—

50 Fig. 1 is a vertical section taken thru the central portion of a tank and showing my improved flush valve associated therewith.

Fig. 2 is a front elevational view of the valve with the upper portion thereof in vertical section.

Fig. 3 is an enlarged vertical section taken on the line 3—3 of Fig. 1.

Fig. 4 is a vertical section taken lengthwise thru the center of the valve and showing the same in open or flushing position.

Fig. 5 is a horizontal section taken on the line 5—5 of Fig. 4.

Fig. 6 is an elevational view of a tank and bowl and showing my improved flush valve associated therewith.

Referring by numerals to the accompanying drawings which illustrate a practical embodiment of my invention, 10 designates a tank that is adapted to contain a substantial volume of flushing water, said tank being of air-tight construction and receiving its supply of water from a pipe 11 that is connected to a suitable source of supply, for instance, the city mains, said supply pipe 11 leading to the bottom of the tank 10 and being connected in any suitable manner to one leg of an inverted U-shaped pipe 12 that is positioned in the lower portion of tank 10 with its open end terminating near the bottom of said tank.

My improved flush valve includes a substantially L-shaped casting, the upright portion 13 of which occupies a position a short 85 distance in front of the lower portion of tank 10, and projecting from the lower portion of the upright member 13, toward the tank 10, is a horizontally disposed, tubular member 14 that is connected by a suitable coupling 90

15, and short tube or nipple 16 to the lower front portion of tank 10.

The lower portion of upright member 13 of the valve is provided with a substantially cylindrical float chamber 17, and removably seated in the upper portion of this chamber is a ring 18 on the upper surface of which is formed a rib 19 that functions as a valve seat. The chamber 20 above ring 18 functions as a valve chamber, and arranged to move vertically therein, is a disc valve 21 to the underside of which is secured, in any suitable manner, a disc 22 of rubber, leather or composition, and which is adapted to rest 10 directly on the valve seat 19.

The top of valve chamber 20 is closed by a screw cap 23 that is removably positioned on the upper portion of the valve body 13, and formed thru the center of said cap is an 20 opening that is provided with a gland 24 thru which operates an axially disposed stem 25, that projects upwardly from valve 21.

Formed on the underside of cap 23, is a concentric rib 26 that functions as a seat 25 for a packing disc 27, which latter is secured in any suitable manner on top of disc 21. As a result of the construction just described, the joint between the stem 25 and the gland 24 is effectually packed by the engagement 30 of the packing disc 27 against the seat 26 when valve 21 is elevated.

Removably positioned on top of cap 23, is a relatively small cap 28 and journaled therein, is a horizontally disposed shaft 29, on which is formed eccentric 30, that bears 35 against the upper end of stem 25.

One end of shaft 29 projects thru the side wall of the cap 28, and carried by said projecting end is a handle 31.

40 A small torsion spring 32 is arranged on the projecting end of shaft 29 and normally holds same with the eccentric 30 in its lowermost position, thereby holding stem 25 at its lower limit of movement and with the packing member 22 on the underside of disc valve 21 upon seat 19.

Formed integral with and extending downward from the lower end of the body 13 of the valve, is a short tubular member 33 that is connected by a suitable union 34 with the tubular flushing inlet member 35 of a bowl 36, and formed around the opening that establishes communication between the float chamber 17 and the opening thru the tubular member 33, is a concentric valve seat 37.

Arranged to move freely within the float chamber 17, is a substantially cylindrical float 38 provided on its underside with a packing disc 39 that is adapted to rest on seat 37, and thereby close the opening into tubular member 33.

Concentrically arranged within the float 65 is a wall 39, and arranged in the lower por-

tion thereof, is a bushing 40 within which is formed a circumferential groove 41.

Pivottally mounted on a lug 42 that is arranged in the upper portion of tubular member 33, is the lower end of an arm 43 and 70 said arm extends upwardly thru the bushing 40, and its upper end terminates in a head 44 which, when the float is elevated, is adapted to engage in the groove 41.

Formed integral with the lower portion of 75 the arm 43, and extending downwardly into the opening thru tubular member 33, is an arm 45, and formed integral with the lower end thereof, is an inclined plate 46.

Formed thru the wall of the body 13 of 80 the valve, is a vertically disposed duct, the upper end of which communicates with the valve chamber 20 above ring 18 and the lower end of this duct communicates with the opening thru tubular member 33, just 85 below lug 42.

Formed integral with the upper side of the horizontally disposed member 14 of the valve body and with the adjacent side of valve body 13, is a block 48 thru which is formed a vertically disposed duct 49, and screw seated in the upper portion of said duct, is a cap 50 having a depending tubular portion 51, and formed in the latter, 90 is an aperture 52 that registers with a short duct 33 that extends upwardly thru the wall of the valve body 13, and the upper end of said duct being open to the atmosphere just 95 above cap 50.

The lower end of the tubular portion 51 100 of cap 50 functions as a seat for a small spherical check valve 54, which is buoyant and said check valve being loosely arranged in the intermediate portion of a duct 49 and being retained against downward movement 105 therein by two or more lugs 55 that project into the duct 49.

Formed thru the upper portion of the horizontally disposed member 14 of the valve body and communicating with the lower end 110 of duct 49, is a horizontally disposed duct 56, the inner end of which communicates with a tubular member 57, the same leading downwardly across the inner portion of the opening thru member 14 and the lower end 115 of said tubular member 57 communicating with a short duct 58 that communicates with the opening thru tubular member 33.

Connected to the opposite end of the duct 56, is one end of a tube 59 that extends horizontally thru the connection 16, and thence upwardly in tank 10, and the upper portion of said tube is bent into U-shape, as designated by 60, and the depending end of said bent portion is provided with an upwardly seating check valve 61.

Under normal conditions, water that enters thru supply pipe 11 and the gooseneck 12, rises in tank 10 to a level where it engages check valve 61 and forces the same 130

onto its seat, thereby closing the air passage thru tube 59, ducts 56, 57 and 58, and the water within the tank under pressure, compresses, to a certain degree, air that is 5 trapped in the upper portion of the tank above the level of the water.

Valve 21 is retained on seat 19 by eccentric 10 30 that engages the upper end of stem 25, thereby closing the opening thru ring 18, and water under the same pressure as the 15 water in tank 10 fills the float chamber 17 and exerting downward pressure on float 39, maintains the same on seat 37, and the packing disc 39 on the underside of the 20 float effectually prevents leakage of water past the seat 37 and thru outlet connection 33 that leads to the bowl.

To operate the flush valve, handle 31 is 25 engaged and swung into a substantially upright position, thereby permitting valve 21 to rise as a result of pressure of the water against its underface, and as the valve is thus lifted from its seat, the pressure of the water trapped in tank 10 and the valve housing, will be lowered so as to permit float 38 to rise in float chamber 17, thereby opening the upper end of outlet 33, which permits water from tank 10 and in the connection 16 and 14, to flow downwardly thru outlet 30 33, which flow is greatly accelerated by the pressure of the air trapped in tank 10 above the body of water therein.

Any water that passes upwardly thru 35 ring 18 into valve chamber 20 will, in due time, discharge downwardly thru duct 47, into outlet 33. As float 38 is elevated in its chamber, the force of water passing downwardly thru outlet 33 will bear against the upper face of inclined plate 46 so as to move 40 the same downwardly and rearwardly, thereby swinging the upper end of arm 43 so that the head 44 thereon engages in groove 41 in the bushing 40, and thus the float is maintained in elevated position while the water from tank 10 is discharging thru the valve 45 and the outlet 33.

After the water has discharged thru the valve, as just described, the weight of the float 38 will effect a disengagement of the head 44 from the groove 41, and the float 50 will move downwardly until the packing disc 39 is positioned on seat 37.

After pressure on the handle 31 is released, 55 spring 32 will rotate shaft 29 so as to cause cam 30 to engage and move stem 25 downwardly, thereby reseating the packing member 22 on the underside of valve 21 upon the seat 19.

If, when valve 21 is actuated to effect the 60 flushing operation, as just described, there should be any water forced past check valve 61 and thru pipe 59 and duct 60, said water will strike float check valve 54, and force the same upwardly against its seat on the lower 65 end of tubular member 51, thereby prevent-

ing said water from passing outwardly thru air inlet duct 53, and thus any water passing thru tube 59 and duct 56 will be caused to pass out thru ducts 57 and 58 that lead to the outlet 33.

When the valve is actuated, as just described, and the level of the body of water lowers within tank 10, a short distance, valve 61 will leave its seat, thereby permitting air to enter duct 53 and pass downwardly thru 70 duct 49, thence thru duct 56, and tube 59, so as to break the seal in the upper portion of tank 10 and consequently, permitting the water to freely and quickly discharge therefrom.

In some instances, it may be found advantageous and desirable to utilize in the place of the tank 10, a vertically disposed pipe or like container that is arranged in the wall to the rear of the bowl with which my 85 improved flush valve is associated.

Thus, it will be seen that I have provided a toilet tank flush valve that is relatively simple in construction, inexpensive of manufacture, capable of being readily assembled 90 and installed, and which valve is especially effective, due to the fact that air that is trapped in the upper portion of the water storage tank is utilized for accelerating the 95 flushing operation when the valve is opened.

It will be understood that minor changes in the size, form and construction of the various parts of my improved toilet tank flush valve may be made and substituted for those herein shown and described without departing from the spirit of my invention, the scope of which is set forth in the appended 100 claims.

I claim as my invention:

1. In a toilet tank flush valve, a housing 105 having a float chamber, said chamber having an inlet opening and outlet opening, a float arranged within said chamber for normally closing said outlet opening, said float having a chamber, a pivoted detent projecting into said chamber and adapted to be actuated by the flow of water from the tank and through the flush valve for engaging the float within its chamber and holding said float elevated within the float chamber, a tank connected to said inlet opening, a tank 110 adapted to contain water under pressure, manually operable means for relieving the pressure of the water within said float chamber and tank, and means for admitting atmospheric air to said tank.

2. In a toilet tank flush valve, a housing having a float chamber, said chamber having an inlet opening and outlet opening, a float arranged within said chamber for normally closing said outlet opening, a tank connected to said inlet opening, a tank adapted to contain water under pressure, manually operable means for relieving the pressure of the water within said float chamber and tank, 115 120 125 130

- self-acting, releasable means adapted to be actuated by the flow of water from tank and flush valve for engaging and holding the float in elevated position within the chamber.
3. In a flush valve, a housing having a float chamber, said chamber having inlet and outlet openings, a float arranged within said float chamber for normally closing said outlet opening, a manually operable valve normally closing the upper end of the float chamber, a duct for carrying off water that passes thru the opening at the upper end of the float chamber, and self acting releasable means adapted to be actuated by the water discharging from the float chamber for maintaining the float in elevated position.
4. In a flush valve, a housing having a float chamber, said chamber having inlet and outlet openings, a float arranged within said float chamber for normally closing said outlet opening, a manually operable valve normally closing the upper end of the float chamber, a duct for carrying off water that passes thru the opening at the upper end of the float chamber, self-acting releasable means adapted to be actuated by the water discharging from the float chamber for maintaining the float in elevated position, a tank connected to the inlet opening into the float chamber, and an air inlet duct leading from the exterior of the valve to said tank, which duct includes a check valve.
5. In a flush valve, a housing having a float chamber, said chamber having inlet and outlet openings, a float arranged within said float chamber for normally closing said outlet opening, a manually operable valve normally closing the upper end of the float chamber, a duct for carrying off water that passes thru the opening at the upper end of the float chamber, self-acting releasable means adapted to be actuated by the water discharging from the float chamber for engaging and maintaining the float in elevated position, a tank connected to the inlet opening into the float chamber, an air inlet duct leading from the exterior of the valve to said tank, which duct includes a check valve, and a branch duct leading from said air inlet duct to the outlet from the float chamber at a point below the same.
6. In a toilet-tank flush valve, a housing having a float chamber, said chamber having inlet and outlet openings, a float within said chamber for normally closing said outlet opening, and means actuated by the flow of water thru said outlet opening for engaging and holding the float in elevated position during the passage of water thru the float chamber, which holding means is automatically released from its engagement with the float by the weight of the latter at the termination of the flow of water through the valve.
7. In a toilet tank flush valve, a housing provided with a float chamber, said chamber having inlet and outlet openings, a float for normally closing the outlet opening from said chamber, a detent pivotally mounted in the valve below the float and adapted to be actuated by the flow of water through the valve for engaging and holding the float elevated, which detent is automatically released from its engagement with the float by the weight of the latter at the termination of the flow of water through the valve, an air-tight tank connected to the inlet opening of said float chamber, means for supplying water under pressure to said tank and float chamber, and a manually operable valve normally closing and opening at the upper end of the float chamber.
8. In a toilet tank flush valve, a housing provided with a float chamber, said chamber having inlet and outlet openings, a float for normally closing the outlet opening from said chamber, a detent pivotally mounted in the valve below the float and adapted to be actuated by the flow of water through the valve for engaging and holding the float elevated, which detent is automatically released from its engagement with the float by the weight of the latter at the termination of the flow of water through the valve, an air-tight tank connected to the inlet opening of said float chamber, means for supplying water under pressure to said tank and float chamber, a manually operable valve normally closing and opening at the upper end of the float chamber, and a pressure outlet duct leading from the interior of the housing above the float chamber therein.
9. In a toilet tank flush valve, a housing provided with a float chamber, said chamber having inlet and outlet openings, a float for normally closing the outlet opening from said chamber, an air-tight tank connected to the inlet opening of said float chamber, a detent pivotally mounted in the valve below the float and adapted to be actuated by the flow of water through the valve for engaging and holding the float elevated, which detent is automatically released from its engagement with the float by the weight of the latter at the termination of the flow of water through the valve, means for supplying water under pressure to said tank, and float chamber, a manually operable valve normally closing and opening at the upper end of the float chamber, a pressure outlet duct leading from the interior of the housing above the float chamber therein, and a water pressure tank connected to the inlet opening of the float chamber.
10. In a toilet tank flush valve, a housing provided with a float chamber, said chamber having inlet and outlet openings, a float for normally closing the outlet opening from said chamber, an air-tight tank con-

nected to the inlet opening from said float chamber, means for supplying water under pressure to said tank, and float chamber, a manually operable valve normally closing
5 and opening at the upper end of the float chamber, a pressure outlet duct leading from the interior of the housing above the float chamber therein, a water pressure tank connected to the inlet opening of the float chamber, and means including a check valve for permitting air to enter the pressure tank when the pressure therein drops to atmospheric pressure.

In testimony whereof I affix my signature.
